UNITED STATES PATENT OFFICE.

AUGUST H. LENZ, OF FOND DU LAC, WISCONSIN.

ATTACHMENT FOR GRINDING THREAD-TOOL BITS.

1,304,070.

Specification of Letters Patent. Patented May 20, 1919.

Application filed December 17, 1917. Serial No. 207,613.

To all whom it may concern:

Be it known that I, AUGUST H. LENZ, a citizen of the United States, residing at Fond du Lac, in the county of Fond du Lac 5 and State of Wisconsin, have invented certain new and useful Improvements in Attachments for Grinding Thread-Tool Bits, of which the following is a specification.

This invention relates to an attachment 10 for grinding thread tool bits and has for its object the production of a simple and efficient means for adjustably holding the tool bit in engagement with a grinding medium.

Another object of this invention is the 15 production of a simple and efficient means for feeding the tool bit toward the grinding medium.

With these and other objects in view this 20 invention consists of certain novel constructions, combinations and arrangements of parts as will be hereinafter fully described and claimed.

In the drawings:—

Figure 1 is a top plan view of the device, 25 Fig. 2 is a front elevation thereof,

Fig. 3 is a section taken on line 3—3 of Fig. 2,

Fig. 4 is a section taken on line 4—4 of Fig. 2,

Fig. 5 is a bottom plan view of the gage 30 plate removed from the supporting means along line 5—5 of Fig. 3,

Fig. 6 is a bottom plan view of the rack plate and operating means therefor,

Fig. 7 is a transverse sectional view 35 through the gage plate retaining means.

By referring to the drawings, it will be seen that 1 designates the base which is provided with a pair of depending ears 2 which 40 are engaged by means of a yoke 3 carried upon a supporting post 4. This supporting post 4 is adapted to fit in the place of the rest plate on the emery wheel frame. The base 1 is provided with beveled side edges 5 which engage the beveled track ways 6 carried upon the bottom of the rack plate 7. A 45 filler strip 8 is carried by one of the track ways 6 and constitutes a wearing plate for engaging the base 1. Adjusting screws 9 pass through the track ways 6 and engage 50 the plate 8 for adjusting the same relative to the base 1, and permitting this plate 8 to be adjusted to take up the wear upon the base 1.

A shaft 10 extends through the ears 11 carried by the base 1 and this shaft 10 sup-

ports a pinion 11' which pinion 11' meshes with a rack bar 12 formed upon the bottom of the rack plate 7, for the purpose of shifting the rack plate 7 to a desired position 60 upon the base 1. A suitable crank 13 is fitted over the outer end of the shaft 10 and is connected thereto by means of a pin 14 which is carried thereby, and fits within the notches 15 formed in the crank 13. 65

A track plate 16 is extended across the rack plate 7 as shown in Fig. 7 and this track plate 16 is provided with beveled side edges 17 for engaging the beveled track ways 18 formed upon the bottom of the gage 70 plate 19 as shown in Fig. 5. A threaded socket plate 20 is carried by the track plate 16 and this socket plate 20 receives a threaded adjusting pin 21, which passes through and is loosely mounted upon the ear 22 carried by the gage plate 19. An operating knob 23 is carried by the outer end of the threaded pin 21 for the purpose of facilitating the rotation of the pin 21 and the transverse adjustment of the gage plate 19 across 75 the rack plate 7.

The gage plate 19 comprises a substantially semi-circular body, having a straight front face 24 and a curved rear face 25. The rear face 25 is provided with a plurality 80 of gage notches 26 formed in the rear thereof, as shown clearly in Fig. 5 of the drawings. These notches 26 are arranged upon the arc of a circle, and are marked from the center line zero toward each corner reading as follows:— $14\frac{1}{2}^{\circ}$, 30° , 45° , 60° , $75\frac{1}{2}^{\circ}$ and 90° . It of course should be understood that the gage plate 19 may be graduated in any suitable or desired manner. 90

A tool engaging clamp 27 is pivotally mounted upon the gage plate 19 by means of a screw 28 and this clamp 27 is provided with a stationary projecting jaw 29. A sliding adjustable jaw 30 is carried by the clamp 27 and this adjustable jaw 30 carries a plurality of overhanging plates 31 which plates overhang the clamp 27 as shown in Fig. 4 for holding the adjustable jaw 30 against accidental displacement. A socket plate 32 is carried by the adjustable jaw 30 and receives a lower threaded end of the adjusting screw 33, which is carried by the overhanging plate 34. An operating knob 35 is carried by the upper end of the threaded pin 33 as shown clearly in Fig. 3 for the 100 purpose of permitting the adjustment of the adjustable jaw 30 upon the clamp 27. 105

The vertically extending portion of the clamp 27 is reinforced by means of a bracing web 36 as shown in Fig. 4.

A latch 37 is pivotally mounted within a socket 38 carried by the rear of the clamp, the socket 38 being formed in a housing 39 carried by the clamp 27. A coil spring 40 is secured to the clamp 27 and engages the lower end of the latch 37 and normally holds the lower end of the latch 37 within one of the notches 26 formed in the gage plate 19.

The principal object of the present invention is to produce an efficient means for grinding a thread tool bit for cutting a 29°, 15 60° and square threads. Further it should be understood that the bit may be ground to a number of different degrees if so desired, owing to the adjustments which are made possible, by the present invention. By means 20 of the present device, a workman will be enabled to efficiently grind a tool bit at a proper angle without regard to the grinding surface of the emery wheel, in view of the fact that the tool bit may be held in a proper 25 position for permitting the emery wheel to grind the point of the bit at a desired angle.

It is desirous to have the latch 37 operate with the least amount of friction and for this reason the latch 37 is pivotally mounted 30 between the cone shaped ends 37' of the adjusting screws or supporting screws.

The operation of the device is as follows:

A tool bit 41 is clamped between the adjustable jaw 30 and the stationary jaw 29 35 and the bit is swung to the desired position by adjusting the clamp 36, upon the gage plate 19 and permitting the latch 37 to engage the desired notch 26. The tool bit 41 may be moved across the face of the emery 40 wheel or grinding medium by operating the crank 13, thereby rotating the operating pinion 11. In this way the rack plate 7 will be shifted upon the base 1, for the purpose of moving the tool 41 in the desired direction. 45 The gage plate 19 may be shifted transversely across the rack plate 7 by means of the adjusting screw or pin 21, thereby moving the tool bit 41 into or out of engagement with the grinding medium.

50 It should be of course understood that certain obvious detail mechanical changes may be made in the present device without departing from the spirit of the invention, so long as these changes fall within the scope 55 of the appended claims.

What is claimed is:—

1. In a device of the class described, the combination of a supporting means, a tool engaging clamp pivotally mounted upon said 60 supporting means and comprising a vertically extending body, a sliding jaw which is substantially U-shaped in top plan engaging

the front and side surfaces of said body, plates fixed upon said jaw and engaging the rear surfaces of said body for slidably holding said jaw upon said body, said body having a fixed jaw at its lower portion in the path of movement of the sliding jaw, an overhanging plate carried by the upper end of said body, a screw passing through the overhanging plate and engaging said sliding jaw, whereby the sliding jaw may be adjusted with respect to the fixed jaw. 65 70 75

2. In a device of the class described, the combination of a supporting means, said supporting means including a gage plate having notches in one periphery, an elongated fixed jaw pivotally mounted upon said gage plate, a body extending vertically from said jaw, a sliding jaw movable upon said body, a reinforcing web carried by said body and formed on said fixed jaw for reinforcing the body, a vertically extending housing formed on the rear end of said fixed jaw, said housing having a vertical socket therein, a latch pivotally mounted within said socket and extending from said socket adjacent the upper end thereof, coiled springs connected to said housing within the socket at the lower portion thereof and also connected to said latch, thus holding said latch within a selected socket for holding said fixed jaw in a set position upon said gage plate although the latch may be swung by movement of its upper end into said socket to move the lower end thereof from a notch thus permitting the fixed jaw to be swung upon a gage plate whereupon the latch may be released to again fit within another selected notch. 80 85 90 95

3. In a device of the class described, the combination of a rack plate means for adjustably supporting said rack plate, a track plate fixed upon said rack plate and extending transversely thereof, said track plate being centrally channeled a socket plate secured within the channel of the track plate, a gage plate having trackways thereon engaging said track plate, thus slidably mounting the gage plate upon said track plate, said gage plate having a depending ear in alignment with said socket plate, a screw passing through said ear and into the socket plate, whereby said gage plate may be moved longitudinally of said track plate by the movement of the screw within the socket plate, an implement retaining means mounted upon said gage plate. 100 105 110 115

In testimony whereof I affix my signature in presence of two witnesses.

AUGUST H. LENZ.
